(57) CLAIM

The ornamental design for a coin holder, as shown and described.

DESCRIPTION

FIG. 1 is a top plan view of a coin holder showing my new design, which is a mirror image of the bottom plan view; FIG. 2 is a cross-sectional view taken along lines 2—2 of FIG. 1; and, FIG. 3 is a perspective view.

No claim is made to the phantom outline, which is for illustrative and environmental purposes only.
